TICKET ISSUING AND PRINTING MACHINE

Edgar S. Spargo, Miami Springs, Fla., assignor
to Sparson Engineering Corporation, Miami
Springs, Fla., a corporation of Florida

Application June 1, 1949, Serial No. 96,527

24 Claims. (Cl. 101—69)

1

This invention relates to ticket printing and issuing machines, particularly to machines for issuing tickets, for example, at races where the pari-mutuel system of calculating betting odds is employed, and has for its primary object to provide an improved electrically operated ticket issuing machine.

Another object of the invention is to provide a universal ticket issuing machine adapted for issuing one or two-numbered tickets, thereby enabling the machine to be used for Quiniela (wherein two entries in one race are selected) and Daily Double (wherein one entry in each of two specified races are selected) wagering, which require the selection of an entry in two races, as well as for the usual style and denominations of mutuel tickets requiring selection of single entries and single races.

Yet another object of the invention is to provide an electric ticket printing and issuing machine made of relatively few and standard working parts in which gears, chain drives, and other mechanical inter-connected motivating mechanisms have been substantially eliminated.

Still another object of the invention is to provide an improved machine from which a ticket may not be removed without recordation thereof.

A further object of the invention is to provide a simple electrical means for locking and unlocking a ticket issuing machine, thereby restricting the machine to authorized use only and thus preventing unauthorized misuse thereof.

A still further object of the invention is to provide a machine that is subject to the control of an authorized person who directs the interval during which the attendant may operate the machine.

Yet a further object of the invention is to provide a machine that is adapted to print tickets having variable codes, style, and race numbers, so that counterfeiting of tickets is prevented.

A still further object of the invention is to provide a machine in which code and race changing means of a simple and readily operated mechanism are incorporated, so that the code may be quickly changed by an electrical impulse at the close of each selling period.

Another object of the invention is to provide an improved electrically operated printing and ticket issuing machine in which the various steps of printing, moving the ticket paper, severing the ticket, registering, and ejecting the ticket from the machine are under direct control of a cycling mechanism, thereby assuring an accurate count of all tickets issued by the machine.

With the above objects in view, an embodiment

2

of the invention herein discloses a ticket printing and issuing machine, which upon operation of the desired key or keys selection of the corresponding type is obtained through energization of predetermined relays and solenoids, the type for the several codes, races, and numbers being carried upon horizontally slideable bars. An escapement device coupled to a solenoid is provided for each of the code and race change bars, so that each of these bars is set to a different position, in response to its associated solenoid, step-by-step from the first face to the last race. Similarly, a solenoid is provided for moving each of the number bars to its fullest travel, each bar, however, being arrested at a predetermined position by a transversely movable pin engaging the forward end of the bar, each pin being controlled by a corresponding relay and solenoid, which are coordinated with the digital keys. Following selection of a particular number or numbers and with the selected type in the printing position, an electrically operated timing mechanism is set into motion and through a series of cams thereon energizes a series of electric circuits in timed sequence, whereby the operations of printing, paper moving, severing, registering, and ejecting the ticket are accomplished in a rapid, step-by-step, manner. The machine is so arranged that additional tickets cannot be issued following official termination of the selling period, although should a ticket have been initiated just prior to said termination, the timing mechanism will complete its cycle to issue this ticket. Provision is also made in the machine for notifying the attendant when the paper roll supply is approaching depletion and for reversing the travel of the ink ribbon when required.

A more complete understanding of the invention will be obtained from the following description of a preferred embodiment thereof, taken in conjunction with the accompanying drawings in which:

Figure 1 shows a perspective view, facing the left front corner thereof, of the ticket printing and issuing machine of this invention;

Figure 2 is a perspective view of the machine, facing the right front corner, with certain parts of the casing removed to show the timing mechanism and power rectifier;

Figure 3 is a sectional view taken along line 3—3 of Figure 2 in the direction of the arrows illustrating the paper supply roll and paper advancing mechanism in the lower portion, the type bars and printing platen in the upper central portion, and the electrical relays and solenoids in the upper right portion;

Figure 4 is a top plan view, with certain parts removed for clarity, showing the number control relays, ejector mechanism, ribbon mechanism, counter, and keyboard for a Quiniela race;

Figure 5 is a perspective rear view, with certain parts removed for clarity, showing the type bars, mechanism for operating number selector type bars, and paper advancing mechanism;

Figure 6 is a front view of a sample ticket for a Quiniela race adapted to be printed and is used by the machine of this invention;

Figure 7 is a perspective view opposite to that of Figure 5 showing the selector pin-escape mechanism for actuating the code and race change type bars, as well as the paper pressure roller mechanism;

Figure 7a is a perspective view of the rear of the rocker arm shown in Figure 7 for the code bar;

Figure 8 is a detailed perspective view of the timer, shown in Figure 1, for controlling the operating cycle of the machine;

Figure 9 is a perspective view showing the ejector mechanism, counting trigger and associated electrical contact spring, cutting blade 25 solenoid, and portion of the printing platen assembly at the lowermost part;

Figure 10 is a more detailed and complete view of the printing platen assembly shown in Figure 9;

Figure 11 is a perspective view of the cutting blade mechanism including connection to the actuating solenoid at the left part thereof;

Figure 12 is a perspective view of a portion of the knife blade mechanism and ejector mechanism, with parts cut away to more clearly bring out the relationship between the counting trigger and contact spring;

Figure 13 is an electric schematic diagram of the control relays, solenoids, keys, etc., for a Quiniela arrangement constructed in accordance with the invention;

Figure 14 shows in diagrammatic form the timing apparatus and other common equipment adapted to be connected to the circuit shown in Figure 13, as well as to the circuits shown in Figures 16, 17, 19, and 20, to be referred to hereinafter;

Figures 15 and 16, taken together with Figure 14, show a schematic diagram of the arrangement required for a Daily Double horse race;

Figure 17, taken together with Figure 14, shows a schematic arrangement for a Daily Double dog race;

Figures 18 and 19, taken together with Figure 14, show a schematic arrangement for regular horse race including win, place, or show, or the combination thereof; and

Figure 20, taken together with Figure 14, shows a schematic arrangement for a dog race including win, place, or show.

Referring now to the drawings, particularly to Figures 1, 2, and 3, there is shown a cabinet or casing 25 for the machine of this invention comprising a top 26 with a ticket slot 24, left side 27, right side 28, bottom 29, and front 30. The casing is preferably made of sheet metal of appropriate gauge in order to minimize the weight thereof and at the same time to provide sufficient rigidity as a mounting support for the various pieces of equipment carried thereby. The upper portion of the front 30 is shown provided with a sloping shelf 31 for mounting a plurality of conventional push button keys 32 and

a toggle switch 33, while immediately thereunder is shown a plurality of toggle switches 34 mounted upon a vertical plate 36 disposed inwardly from the face of the front 30, as more clearly seen in Figure 3. The shelf 31 may be attached to the front 30 in any suitable manner, as by screws 37. It is, of course, understood that the number of push buttons 32 and associated toggle switches 34 may be varied to accommodate the particular type of race for which the machine is to be arranged, the number of buttons and switches being greater for a Daily Doubles race and fewer for a single race involving Win, Place, and Show, as will be readily apparent from the electrical circuit diagrams. In the embodiment shown, the keys and toggle switches are illustrative of a Quiniela race and the description hereinafter will be particularly directed to this type of race.

The lower portion of the front 30 is provided with a movable panel 38, hingedly secured to the bottom 29 by a pair of hinges 39 for permitting access to the interior of the cabinet. A recess 40 in the upper portion of the panel 38 is provided for facilitating movement thereof from its closed to open position.

A pair of male sockets 41 is shown in the left side 27 for connecting the various electrical circuits to the machine, including the power supply and leads from the totalizer (not shown). At the top 26 is shown a counter 35 of any suitable type, preferably an electric counter, for registering the sale of each ticket issued by the machine during the day, which counter at the start of the day is set to zero, through a special key (not shown), thereby preventing unauthorized changes in setting. By providing a separate counter for each machine, a breakdown of the total sales of the day may be readily ascertained, particularly for the discovery and correction of errors.

Type bars

The various type will now be described. Referring particularly to Figures 3 and 5, there is shown an elongated bar 42, of metal or the like, having a plurality of grooves 43 extending the entire length thereof, in this instance five grooves, each of which is formed with a restricted aperture or throat 44 and an enlarged opening 46, the material intermediate the grooves 43 being substantially T-shaped, as is readily apparent. Within the grooves are disposed slideable type bars 47 of substantially "I" configuration in section having an inner flange 48 disposed within the enlarged opening 46, a web 49 disposed in the throat 44, and an outer front flange disposed externally of the groove and having a predetermined type, as will be brought out hereinafter, on its face for printing purposes.

In the first groove 43, reading from top to bottom of Figures 3 and 5, is shown the type bar 47 which carries a plurality of codes 51 thereon, a separate one for each race. The codes may consist of words or distinctive characters and there will naturally be as many different words or characters as there are races for which the machine will be used for that particular day. For purposes of description this bar will be termed the code change bar 51. The code will be changed for each race, in a manner to be described hereinafter, and this is one of the features provided in this invention to prevent forgeries or alterations of authorized tickets.

In the next two grooves 43, below the code change bar, are shown two number bars, a lower

number bar 52 having the numerals 1 to 8 and the character T (for Test) reading from left to right, as viewed in Figure 5; and an upper number bar 53 in which the characters start with "No." and then continue with 1 to 8 and T, as shown in Figure 5; the characters on the upper number bar however, read from right to left. It might be mentioned at this point that in a physical sense the upper number bar 53 is underneath the lower number bar 52 and this is done in order to correspond with the positions of the numbers actually appearing on a ticket, which ticket is upside down when printed in the machine. Both number bars may be arranged for use in all types of races, such as for Quiniela, Daily Doubles, or single entry races and it is, of course, understood that instead of a series of eight numbers on these bars a different series of numbers may be used. In Quiniela and Daily Doubles races the numbers on both bars are used. However, in a single race where the numbers of the upper number bar 53 are not employed, the characterization "No." will appear in place of the upper digit. Thus in Figure 6 the upper numeral 4 will be replaced by "No." in this event. It will, therefore, be realized that the two number bars 52 and 53 must be disposed at a predetermined distance from the vertical center of the bar 42, so as to assure that the correct character will always be printed. From the above, it will be readily seen that the character "No." on the upper number bar 53 will be normally located at the vertical center of the bar 42, or printing position, thereby eliminating the necessity of providing for any movement whatever of the upper number bar 53.

In the fourth groove from the top is slidably mounted a "race change" bar 54, which includes on the face thereof in spaced, numerical sequence the total number of races to be run for a particular day. The number of races varies, being usually seven or eight for horses, nine for Jai Alai, and ten for dog races and, when the machine is used for a "Doubles" race, the races in which the Doubles ticket is effective is so noted, that is, horseracing doubles are generally first and second races, so that the characterization on this bar would be 1st and 2nd race. In dog races and Jai Alai the custom is 1st and 3rd or 2nd and 3rd.

In the fifth groove from the top is disposed the denomination or "style bar" 56 which indicates the type of race for which the machine is to be used for a certain day. In other words, the type appearing thereon could be Quiniela, Daily Double, Win, Place, Show, or in denominations, Two, Five, Ten, or in fact any combination that the mutuel manager might choose to use.

In viewing both Figures 3 and 5 and, as mentioned hereinbefore, it is to be noted that the type is arranged in reverse relationship, in order that a ticket printed thereby will be upside-down. This is done so that the ticket, when ejected from the machine, will be tossed directly in front of the purchaser in the correct position for instant readability. Thus looking at the type in Figure 5 and reading from bottom to top, there are shown (1) a race track bar 55, which identifies the track where the race is being run or a racing association and which is changeable through an opening accessible when the lower front panel 33 is opened; (2) the denomination or style bar 56; (3) the race change bar 54; (4) the top number bar 53; (5) the lower number bar 52; (6) the code change bar 51; and (7) a date bar 57, which is inserted in a fixture 58 at the

start of the day when the top 26 is open. An example of a ticket printed in accordance with the above type is shown in Figure 6.

The mechanism for actuating the two number bars 52 and 53 will now be described, with particular reference to Figure 5. The right end of the lower number bar 52, as viewed in Fig. 5, is shown pivotally connected to the upper end of a lever 59, having an inward offset 60, and which lever at its lower end is pivotally connected to a horizontal shelf 61 above the bottom 29 of the casing. Intermediate the ends of the lever 59 is shown a tension spring 62 which is fastened at one end to the lever and at its other end to the side 28 of the casing in order to bias the type bar to the right. The lever 59 adjacent its lower end is shown connected by a spring 63 to the armature 64 of a solenoid 66 mounted upon the shelf 61. Similarly, the upper number bar 53 is resiliently connected through a spring biased lever 67 to an armature 68 of a second solenoid 69, this number bar being biased in the opposite direction to that of the lower number bar 52, namely to the left, as seen in Figure 5. It will be readily apparent from the aforesaid mechanism that upon actuation of solenoids 66 and 69, the lower number bar 52 will be moved to the left and the upper number bar 53 to the right, respectively. As will appear hereinafter, both bars will be arrested at predetermined points in accordance with the digital key 32 that is punched. In the event that a single number is only required to be printed then the right solenoid 66 only will be actuated while the left solenoid 69 will remain de-energized, the character "No." on the upper bar 53 being thereby available for printing purposes.

The full travel of both number bars 52 and 53 will take place when the key 32, designated T (see Fig. 2), is depressed. This key is operated in order to test the free running condition of these bars during the working time of the machine. However, should any other designated key 32 be punched then means must be provided for stopping the number bar at such a point that the corresponding number will register at the printing position. This is accomplished by the projection of a selector pin 71, one for each numbered character, into the path and in advance of the number bar, which pin is slidably disposed in an insulating sleeve 72, fixedly secured, as by a press fit, in a transverse opening 73 in the rectangular bar 42 (see Figs. 3 and 7). One end of each of the pins 71 extends beyond the front of the rectangular bar 42, while the other end of the pin is normally flush with the inner wall 74 (Fig. 7) of the enlarged opening 46 in the groove 43. The nearest end of each of the insulating sleeves 72 projects slightly beyond the front of the bar 42 and in abutting engagement therewith is shown a perforated cross bar 75, preferably of brass, for electrically interconnecting the selector pins 71, for a purpose that will appear hereinafter. A coil spring 76 is rigidly secured at its outer end to the extended portion of each of the pins 71, while the inner end thereof is in abutting engagement with a washer on the cross bar 75, so as to retract the pin to its normally inoperative position. It is obvious that pressure upon the extended front end of the selector pin 71 will cause the other end thereof to project into the enlarged opening 46 and thus stop the bar at a predetermined point in accordance with the pin that has been selected.

Similarly, a perforated cross bar 75' (see Fig. 7) is shown for interconnecting the selector pins 71 associated with the upper number bar 53 and both bars 75 and 75' are interconnected electrically in any suitable manner, as by a strap wire (not shown), to be further described in the electrical circuit description.

Referring to Figure 3, it will be seen that the front end of a selector pin 71 is in abutting engagement with one end of a plunger 77, preferably of insulating material in order to preserve the insulated status of the selector pins 71, slidably disposed within an opening (not shown) of a depending member 78 and in which the other end of the plunger is rigidly secured to a vertical bar 79 adjacent its upper end. The lower end of the vertical bar is secured to one end of a rod 81, the other end of which is connected to an armature of a selector solenoid 82. It will be readily apparent that actuation of one of the selector solenoids 82 will attract the associated armature and correspondingly move the assembly including the connecting rod 81, vertical bar 79, plunger 77, and pin 71 with the result that the free end of the selector pin 71 will be projected into the enlarged opening 46. It will be observed in Figure 3 that the left and right selector solenoids 82 are in their non-operative positions, while the intermediate selector solenoid is in its operative position, so that the associated selector pin 71 is shown disposed in the enlarged opening 46 and in contact with the forward end of the lower number bar 52. Upon de-energization of the intermediate selector solenoid 82 the compressive strength of the spring 76 will force the aforesaid assembly into its inoperative position.

The mechanism for changing the positions of each the code change bar 51 and race change bar 54 is of an electro-mechanical escapement arrangement, the details of which are shown particularly in Figures 7 and 7a. The mechanism for the code change bar 51 is actuated step-by-step by a solenoid 83, the armature of which is connected to one end of a pivotal bell crank 84. A rod 86 interconnects the other end of the bell crank and a lever 87, rigidly coupled to a transverse pin 88, which in turn is fixedly secured to an angularly or diamond shaped rocker plate 89 having three pins 91, 92, 93 projecting from the opposite face thereof. Two of the three pins, namely 91, 92, are disposed at the sides of the rocker plate while the third pin 93 is at the bottom thereof, as seen in Figure 7a. The bottom pin 93 is journaled in the bar 42 while end pins 91 and 92 cooperate with a scalloped or toothed flat bar 94 which in turn is connected by a pin 96, movable in a slot 97 in the bar 42, to the code change bar 51, so that movement of the scalloped bar will cause corresponding movement of the code bar. A tension spring (not shown) is fastened to the end of the code change bar opposite to that where the pin 96 is connected in order to pretension the code change bar. It will be seen, therefore, that actuation of the solenoid 83 will cause the plate 89 through the rod 86 to rock, releasing pin 92 from one of the teeth and thereby permit the scalloped plate to be retracted one step and thus expose another code in the printing position.

Similarly, the race change bar 54 is actuated step-by-step through a solenoid 98, which is pivotally connected to a bell crank 99, thence through a rod 101, lever 102, rocker arm 103, scalloped bar 104, and pin 106 in slot 107 connected to the code change bar. Projections 108,

109 respectively on scalloped bars 94 and 104 enable these bars to be manually retracted to their initial positions at the start of the day's races by the attendant through an access aperture (not shown) in the casing. These two bars are moved once each time the machine is locked after the selling of a race and preliminary to the next race, as will appear hereinafter, so that the maintenance man may test the ticket machine in the interim period.

With respect to the denomination bar 56, which is located in the bottom groove 43, as viewed in Fig. 7, the printing position of the desired indicia on this bar may be regulated also by manual movement, since the style bar is provided with a pin 111 that is freely movable in a slot 112 in the rectangular bar 42. As seen in Figure 7, the pin 111 and, in turn the style bar 56, is in the extreme right position and is held there by means of a resilient element 113, pivotally secured to the rectangular bar 42 by a pin 110 and having an arcuate recess 115 for reception of the pin 111. An outward and downward movement of the resilient element 113 will permit the pin to be removed from the recess and free the way for movement thereof to the left to the succeeding resilient element.

Printing mechanism

Referring to Figures 3, 9, and 10 there is shown a movable printing platen assembly 114 comprising a rigid plate 116 to which are attached shaped resilient strips 117, preferably of rubber, for pressing the ticket against the type. Side plates 118 are rigidly secured to the platen plate 116 in any suitable manner, as by screws 119, and the upper and lower edges of the side plates are slideable in guide ways 121, 122, respectively provided in a top 123 and base 124. Side plates 125 are rigidly secured to the top 123 and base 124, as shown in Figure 9. A solenoid 126 with a bifurcated armature 127 is rigidly mounted upon the base 124 for moving the platen, a rod 128 being secured at its intermediate portion to the armature and at its ends being provided with ears 129 that are attached to the two side plates 118 in any suitable manner, as by welding. Two tension springs 131, secured at one of their ends to posts 132 in the base 124 and at their other ends to the forward ends of the side plates 118, serve to retract the platen to its normal, inoperative position, as shown in Figure 9. The actuated or operative position of the platen is shown in Figure 10.

An inked ribbon 133 (Fig. 4) is interposed between the type and platen for use in making the reading impression on a ticket. A supply reel 134 and a take-up reel 136 are provided for the ribbon, an electro-mechanical escapement mechanism being adapted to rotate the take-up reel and move the ribbon past the type and platen. As seen in the upper left of Figure 4, a ratchet 137 is rigidly connected to the reel 136 and a pawl 138 is in mesh engagement therewith. The pawl is connected to the armature of a solenoid 139, which is actuated once for each ticket printed, a tension spring 141 being adapted to urge the pawl into such mesh engagement and also to retract the armature and pawl upon release of the solenoid 139. A similar escapement mechanism 142 (partially shown) is provided for the supply reel 134. It is, of course, understood that the supply reel may become the take-up reel upon reversal of the ribbon and to provide for automatic reversal thereof, any suitable switching means may be

provided, such as one similar to that shown for the paper supply roll, which will be described hereinafter. A relay 144 and switch 146, to be described later, control the operation of the solenoids 139 and 143. Thus, for a period of time the ribbon will move from right to left, as seen in Figure 4, under the control of solenoid 139, after which upon operation of the circuit reversing switch 146 the ribbon will move from left to right under control of solenoid 143.

Paper moving mechanism

Referring to Figures 3, 5, and 7, the mechanism for supplying the ticket paper to the printing mechanism will now be described. In Figure 3 is shown a paper supply roll 147 freely mounted upon a shaft 148 carried by a pair of spaced, slotted brackets 149 secured to the bottom 29 of the casing. The ticket paper 151 is shown passing around an idler roller 152, thence through an arcuate guideway or chute 153, after which it passes between a pair of corrugated rollers 154 and a resiliently biased rubber roller 156 to a position between the type and platen. The rubber roller 156 is freely carried upon a shaft 157 disposed at the lower ends of a pair of arms 158, the upper ends of which arms are fixedly secured to a shaft 159 journaled in suitable bearings 161 fastened to side plates 162 of a compartment 163 containing this apparatus. A lever arm 164 is affixed to the shaft 159 at a predetermined angle with respect to the arms 158, so that the arms and shaft move as an integral unit. Intermediate the ends of the lever arm 164 is connected one end of a spring 166, the other end of which is secured to the bottom of the compartment 163. To permit the maintenance man to relieve the pressure of the rubber roller 156 against the corrugated rollers, so as to insert or remove the paper 151, the free end of the lever arm 164 is extended through a slot 167 of the compartment 163 and, as is readily apparent in Figure 3, elevation of the arm 164 will separate the rubber roller 156 from the corrugated rollers 154. Rotation of the corrugated roller 154 and, in turn, movement of the paper 151 is accomplished through a solenoid 168 (see Fig. 5) in which the armature thereof is loosely connected to one end of an arm 169, the other end of which is freely connected to one end of a bell crank 171. The other end of the crank 171 is loosely connected to a vertically movable arm 172. The apex 173 of the bell crank is shown pivotally connected to a bracket 174 rigidly attached to the bottom 29 of the casing. The arm 172 is connected to the lower end of a vertically reciprocable rack 176 by a pin 177 which is adapted to move in a vertical slot 178 provided in a bracket 179 fastened to the bottom 29. A spacer 181 is interposed between the bracket 179 and the arm 172. The bracket 179 is also provided with a groove 182 within which the rack 176 is slidable, and the upper end of the rack is held to the bracket 179 by a pin 183 and spacer 184.

In mesh engagement with the rack 176 is shown a pinion 186, which is loosely mounted upon a shaft 187 freely rotatable in bearings 188, which are carried by the side plates 162. A pawl 189 is pivotally carried upon a side face of the pinion 186 and a spring element 191, likewise fastened to the pinion, is adapted to bias the pawl into mesh engagement with a ratchet 192 which is rigidly coupled to the shaft 187. Since the corrugated rollers 154 are also keyed to the shaft 187, it will be readily apparent that

rotation of the pinion 186 in a clockwise direction, as viewed in Figure 5, will produce similar rotation of the ratchet 192 and corrugated rollers 154 and, in view of the pressure of the rubber roller 156 against the ticket paper 151 and corrugated rollers, the ticket paper will be advanced a predetermined distance, namely, the length of a ticket. Such advancement of the paper occurs upon downward movement of the rack 176 under control of the solenoid 168. However, upon release of this solenoid the rack will be retracted to its upper position through a compression spring (not shown) within the solenoid, which spring normally biases the armature outwardly, and it is to be noted that the upward movement of the rack and counterclockwise rotation of the pinion 186 produce no rotational effect upon the ratchet 192 and corrugated rollers 154.

In order to avoid inadvertent exhaustion of the paper supply, an alarm mechanism is provided comprising a lever 193 (Fig. 3), the free end of which is provided with an arcuate protuberance 194 adapted to rest upon the roll 147 and the other end of which is rotatably carried upon a shaft 196 secured to the compartment 163 in any suitable manner. As the paper roll approaches depletion, the protuberance 194 drops accordingly and at a predetermined point the lever 193 contacts and depresses a plunger 197 of a paper roll switch 198 (Fig. 7), having a make and a break contact, attached to one of the compartment sides 162. Upon operation of the switch 198 an electric circuit, to be described hereinafter, is closed for operating a buzzer alarm 35 to advise the attendant of such depletion and the supply circuit to the keyshelf is opened to prevent the issuance of additional tickets. An important advantage of this alarm system is that it not only increases the efficiency of the maintenance man in servicing the machine but also prevents the tail end of the paper, which is usually provided with a piece of tape, from passing into the paper chute 153 and jamming the machine.

Ticket cutter

The mechanism for severing a ticket from the paper roll, after it has been printed and advanced beyond the type and platen, is shown substantially in Figure 11 and to a more or less degree in Figures 3, 4, 9, and 12. Referring particularly to Figure 11, there is shown a stationary cutting blade 201 having a shearing surface 202 in which the upper edge 203 projects slightly beyond the lower edge 204 to present a slightly angled and more efficient cutting surface. The cutting blade 201 is removably attached by screws 206 to a stationary cutting bar 207 which includes a recess 208 on the underside therefor, so that the lower surface of the assembly will be flush with the top 123 (Fig. 9) to which it is secured in any suitable manner. The cutting bar 207 has a transverse, central groove 209 along its side, a cut-out 210 at the corner adjacent the grooved side, and longitudinal grooves 211, 212 adjacent the sides of the stationary blade 201, and an opening 213 in which the rear wall 214 thereof is stepped behind the shearing surface 202 of the removable blade for a purpose that will appear hereinafter. Suitable slots 215 (Fig. 9) are formed in the side plates 125 for passage therethrough of the stationary cutting bar 207.

A movable cutting bar 216 coacts with the stationary blade 201 and is constituted by a right-

angled heel portion 217 having a rearwardly directed tongue 218 movable in the transverse groove 209 and pivotally connected through a pin 219 to the stationary bar 207. The body of the heel portion 217 has a slot 221 for reception of one leg 222 of a bifurcated end portion of a cutting blade 223, the other leg 224 being in abutting engagement with the upper surface of the heel 217. A pair of pins 226 serves to rigidly secure the cutting blade to the heel, so that both heel 217 and cutting blade 223 move as a unit with their pivotal point at pin 219. The cutting blade 223 is provided at its other end with another bifurcated end portion 227 having a lower leg 228 which is movable in the slot 212. The lower leg 222 of the other end portion is movable in slot 211. It is readily apparent that slots 211 and 212 provide guide ways for movement of the cutting blade 223. The inner face of the cutting blade 223 is shown with an arcuate receding shearing edge 229, which in cooperation with the stationary cutting blade, is quite effective in producing a cleanly cut ticket, as it has been found that a straight edge on the movable blade has resulted in ragged edges on the severed ticket.

The left end of the cutting blade 223 is pivotally connected by a pin 231 to one end of a bell crank 232, the other end of which is connected to an armature 233 of a solenoid 234, which latter is secured to one of the side plates 125, as can be readily seen in Figure 9. Operation of the cutting blade solenoid 234 accordingly attracts the armature 233 and, in turn, the movable cutting blade 223, which in being drawn across the upper edge 203 of the stationary cutting blade, shears the printed ticket from the paper roll and becomes seated in the space between the edge 203 and the rear wall 214 of the stationary bar 207. Upon de-energization of the solenoid 234 the movable cutting blade is retracted to its normally open position by a compression spring 236 secured at one end to the pin 231 and at the other end to a pin 237 carried by the side plate 125 (Fig. 9).

Ticket ejecting and registering mechanism

Referring to Figures 4, 9, and 12 there are shown a pair of spaced rubber rollers 238 and 239 freely carried upon a shaft 241 journalled in extension plates 242 rigidly secured to the side plates 125. The rubber rollers 238, 239 are shown projecting through openings 243 and 244, respectively, in a ticket guide plate 246 which is provided with a pair of flanges 247 at the ends thereof for ready attachment to the extension plates 242 in any suitable manner, as by rivets 248. The ticket guide plate 246 is also shown with a central opening 249 in which is normally disposed a trigger 251 for a purpose to be described hereinafter. The rubber rollers 238, 239 respectively abut corrugated rollers 252, 253 fixedly mounted upon a shaft 254 freely journalled in the extension plates 242, as is readily apparent in Figure 9. A collar 256 is rigidly secured to corrugated roller 252 at an outer end thereof and at its inner end is rigidly secured to a ratchet 257 which cooperates with a pawl 258 pivotally mounted upon a triangular arm 259, which in turn is pivoted to one end of an arm 261. The other end of the arm 261 is pivotally connected to one end of a second arm 262, the other end of arm 262 being rigidly coupled to a shaft 263 journalled in the side plates 125. As seen particularly in Figure 12, one end of the shaft 263

extends through the left side plate 125 and has rigidly coupled at its outer end a crank 264, which is pivotally connected through a lever 266 to an armature 267 of a solenoid 268. A spring element 269 is adapted to bias the pawl 258 into mesh engagement with the ratchet 257. It is, therefore, readily apparent that the actuation of the solenoid 268 will impart a sudden rotational movement to the shaft 263 through the crank 264, thereby drawing arms 262 and 261 downward, as viewed in Figure 9, arm 261 rotating triangular arm 259 and pawl 258 to transmit a sudden impulse to the ratchet 257, which in turn rotates both corrugated rollers 252 and 253. Since the corrugated rollers 252 and 253 in conjunction with the rubber rollers 238 and 239 grip the ticket therebetween, there is a springing motion imparted to the rollers which tend to give a tossing action to the ticket which, as mentioned hereinbefore, places the ticket directly in front of the purchaser in the proper position for easy readability.

Returning to the trigger 251, it will be observed in Figure 12 that an intermediate portion thereof is journalled in a bracket 271 rigidly secured to the top 123, while the other end of the trigger 251 is in abutting engagement with an upper spring element 272 of an electric contact assembly 273, which is secured to the top 123. Thus it will be seen that, as the ticket passes by the opening 249 of the guide plate 246, the trigger 251 is moved inwardly and, in view of such movement, the upper contact spring 272 is depressed to close a pair of electric contacts which, as will appear hereinafter, closes an electric circuit for the register or counter 35 in the machine, as well as for the recorder (not shown) in the totalizer (not shown). The trigger, therefore, is actuated substantially at the same time as the ticket is ejected so that this feature of the invention further assures that no ticket can be taken without a registration thereof, thereby preventing any fraudulent withdrawal of a ticket.

Cycling mechanism

The various sequential operations of printing, paper moving, ticket cutting, registering, and ejecting are attained by means of an electric timer unit which, as seen particularly in Figure 8, includes a motor 274 having a shaft 276 rigidly coupled to a gear reduction assembly comprising a pinion 277 in mesh engagement with a gear 278, which in turn is in mesh engagement with a pinion 279. A shaft 281 is rigidly coupled to the pinion 279 and is journalled in spaced plates 282 and 283. A series of cams 284 are rigidly mounted in accordance with a predetermined angular displacement upon the shaft 281 and reading from bottom to top, as viewed in Figure 8, the cams are designated as motor running cam 286, printing cam 287, paper roll moving cam 288, paper cutting cam 289, and finally the ticket ejecting cam 291. It will be noted that each cam includes an adjustable segmental element 292 having an arcuate face, which element is adapted to be set to the desired angular position by means of a set screw (not shown) on the opposite face of the cam proper. The cams 284 are associated with a series of contact springs 293 for actuating the various solenoids in a predetermined sequence, as will appear hereinafter in connection with the description of the electrical circuit.

Electrical description and operation

Referring now to Figs. 13 and 14, the electrical circuit operation of a Quiniela race will be de-

scribed. It will be noted at the bottom of Fig. 13 that there are shown schematically the scratch keys 34, reset key 39, and two rows of digital keys 32, found on the front panel 30 of the ticket issuing machine. Above the keys are schematically shown the selector relays in two banks, one for each row of keys 32, and above the relays are similarly shown two corresponding banks of selector solenoids 82 (also shown on Fig. 3), for projecting the selector pins 71 into the path of the number bars and thereby arresting the bars at the selected points, as already explained. In Fig. 14 is schematically shown the common equipment comprising the cycling mechanism at the right with the associated solenoids connected to the contacts thereof for actuating in sequence the printing, paper moving, paper cutting, and ticket ejecting mechanisms, the ribbon change-over relay, and the various solenoids for the number bars, and code and change-over bars. When the two sheets (Figs. 13 and 14) are arranged side-by-side with their right and left edges respectively abutting, it will be noted that the interconnecting leads match and, therefore, tracing of the circuits is facilitated.

Before the ticket issuing machine is authorized by the steward for the issuance and sale of tickets by the attendant, the machine is first set up with the appropriate type and then tested by the service man to make certain that a ticket having the required information for each particular race will be issued. Accordingly, the service man operates the (test) key 32 which in response thereto sets into motion the various electrical and mechanical apparatus, as will be described step-by-step hereinafter.

A suitable source of energy, preferably of alternating current 1401 (Fig. 14), is shown connected to the machine throughout an appropriate switch (not shown), this energy appearing at terminals + and - thereon. Tracing this energy from the terminals at the bottom of the drawing, it will be seen that negative polarity continues via lead 1402 to the negative terminal at the top left of the drawing; while positive polarity proceeds via lead 1403 through a break contact 1404 of the timer contact springs 293, thence along two paths, one path via lead 1405 to the terminal at the top left of the drawing, and the other path via lead 1407 through paper roll switch break contact 1408, lead 1408, break contact 1409 of machine lock relay 1411, and lead 1412 to terminal 6.

It may be mentioned at this point that the positive supply of electromotive force appearing at terminal 6 and serially passing through the timer contact 1404 is primarily for operation of the relays and associated equipment rendered effective in Fig. 13 by actuation of the digital keys 32, the positive supply for the test relays, test solenoids, and test key being furnished directly without passing through the timer, as will appear hereinafter.

Referring again to Fig. 13, it will be seen that the power supply continues via positive and negative leads 1301 and 1302, respectively, to the various circuit equipment therein. Assuming now that the service man has operated the (test) key 32, a circuit will be closed for the CT selector relay 1303 and the DT selector relay 1304. This circuit may be traced via positive lead 1301 through the test key 32 and thence in two parallel paths, one path through the winding of DT relay 1304, and the other path via lead 1306, through the winding of CT relay 1303, both paths rejoining at lead 1307 and continuing through (re-

set) key 33, lead 1308, and back through the lead 1302 to the negative source of supply.

- DT relay 1304 in operating, at its lower front contact closes an obvious locking circuit therefor; at its uppermost front contact passes positive energy from lead 1301 through the winding of the BT selector solenoid 82, lead 1309, lead 1308, and thence to the negative supply source via lead 1302; at its upper intermediate front contact passes positive energy from lead 1301 via lead 1311, terminal 9 (Fig. 14), lead 1411, through the winding of number bar solenoid 69, and thence via lead 1410, and lead 1402 to the negative source of supply.
15. At the same time the CT relay 1303 in operating, at its lower front contact closes a locking circuit therefor; at its uppermost front contact closes an energizing circuit for the AT selector solenoid 82; and at its upper intermediate front contact closes an energizing circuit for the number bar solenoid 66 and relay 1415, which can be traced from lead 1301 for positive potential from said make contacts, lead 1312, terminal 7 (Fig. 14), lead 1413, parallel windings of number bar solenoid 66 and relay 1415, and thence via leads 1410 and 1402 to the negative source of energy. Relay 1415, in operating, at its break contact opens a path in the operating circuit of the code change solenoid 83 and the race change solenoid 98, thereby preventing operation of said solenoids for a purpose that will appear hereinafter. Both selector solenoids AT82 and BT82 operate to project their associated pins 71 (Fig. 7) into the path of the number bars 52, 53, which are respectively actuated by the solenoids 66 and 69.

The number bars 52, 53 will travel to their fullest extent and upon striking the associated pins 71, will close an operative circuit for the cycling mechanism, as will appear hereinafter. Referring to Figure 14, it will be noted that metallic tip portions 1414, 1416 are shown added to the forward ends of the number bars 53 and 52, respectively, said tip portions being insulated therefrom, and wired to leads 1402 and 1418. Upon electrical contact being made between the associated pins 71 and tips 1414 and 1416, an energizing circuit for the cam motor 274 and the timer lock relay 1417 is rendered effective. This circuit may be traced from positive potential at lead 1406 through the windings of the relay and motor, which are in parallel, lead 1418, tip 1414, pin 71, pin shorting cross bar 75, lead 1419, cross bars 75, tip 1416, and thence over lead 1402 to the negative potential. Relay 1417, in operating, removes the locking latch 1421 from the stop cam 1422, whereupon the motor 274 rotates the shaft 281 and the various cams thereon. The printer cam 287 in rotating, momentarily closes its associated make spring 1423 to render effective an energizing circuit for the printing solenoid 126, which circuit may be traced from positive potential at lead 1403 through make contact 1423, solenoid 126, and thence over lead 1402 to the negative potential.

65. The printing solenoid actuates the platen 116 (see also Fig. 9), as described hereinbefore, to impress upon the ticket paper the information provided by the type.

70. Rotation of the timer shaft 281 causes the protuberance on cam 287 to move past the ticket spring 1423, which opens and de-energizes the solenoid 126 to retract the platen to its normal position. Paper roll moving cam 288 then momentarily closes its associated make spring 1424

to energize the solenoid 168 (also see Fig. 5) in a circuit that can be traced from lead 1403 for positive potential through said contact and solenoid winding to negative potential via lead 1402. Following release of solenoid 168 a similar circuit is provided for the paper cutter cam solenoid 234 (also see Fig. 9) through closure of cam contact 1426, by paper cutter cam 289. In the next step the ticket ejector cam 291 closes the associated make spring 1427 and energizes the ejector solenoid 268 (also see Fig. 9), which circuit therefor may be traced from positive potential at lead 1403, through make contact 1427, winding of solenoid 268, and thence to negative potential via lead 1402.

Closure of contact 1427 also energizes a circuit for the ribbon moving solenoid 139 (also see Fig. 4) in a circuit than can be traced from positive potential at lead 1403, through make contact 1427, break contact 148 adjacent ribbon change-over relay 144, and thence through winding of solenoid 139 to negative potential via lead 1402. As explained hereinbefore, upon ejection of the printed ticket from the machine, the trigger 251 (Fig. 12) is actuated to close two make contacts 1428, 1429 of the contact assembly 273, contacts 1428 and 1429 respectively closing energizing circuits for the counter 35 in the machine and the totalizer counter (not shown), as will be explained hereinafter.

The cycle of the motor 274 is then completed when one of the elements of the contact spring 1404 falls into a well 1430 provided in the cam 286, thereby momentarily interrupting the positive supply potential to the operated relays and solenoids. The motor having made one revolution to issue a ticket, latch 1421 falls into the well 1431 of stop cam 1422 to lock the shaft 281 in a stationary condition and the various operated relays, solenoids, and mechanisms are retracted to their normal positions. Assuming that the apparatus function properly, the machine is now in readiness for issuance of tickets as requested by the purchaser.

In the event the paper roll should approach depletion, the armature of the switch 198 is actuated, as described hereinbefore, to close a circuit for a buzzer 1432, which operates in a circuit that can be traced from positive potential at lead 1407, through operated armature and make contact of switch 198, winding of buzzer 1432, and thence to negative potential via lead 1402. The sound emitted by the buzzer 1432 warns the service man or the attendant of such depletion, so that replacement thereof can be immediately effected.

Assume next that a purchaser requests a ticket comprising the combination 1 and 8. The attendant will strike the corresponding digital keys 32, first, key 1 in the upper row and then key 8 in the lower row, schematically shown in Fig. 13. In response thereto, the main operating circuits for the C1 selector relay 1313 and the D8 selector relay 1314 are momentarily closed, the keys 32 retracting to their normal open positions after release of pressure thereon. The circuit for the C1 relay 1313 may be traced from positive potential via lead 1403, break contact 1404 of the motor running cam 286, lead 1407, break contact 198, lead 1408, break contact 1409, lead 1412, terminal 6, lead 1316, through normally closed scratch key 34, 1 digital key 32, and thence through winding of C1 relay 1313 and reset key 33 to negative potential via leads 1308, 1302 and 1402. C1 relay 1313 in operating, at its lower

intermediate front contact closes a locking circuit therefor, which circuit may be traced from positive potential at lead 1316, through lead 1317, winding of C1 relay 1313, and thence to negative potential at lead 1301. At the lowermost front contact of C1 relay 1313, a circuit is prepared for the counter in the totalizer; at its uppermost front contact a circuit is closed for the A1 solenoid 1318, which circuit may be traced from positive potential at lead 1301 through said contact, lead 1319, through said solenoid winding, and thence to negative potential at lead 1308; at its upper intermediate front contact a circuit is closed for the type bar solenoid 66 and relay 1415 which may be traced from positive potential at lead 1301 through said contact, lead 1321, lead 1312, terminal 7, lead 1413 and thence through windings of relay 1415 and solenoid 66 to negative potential via leads 1410 and 1402.

The circuit for the D8 selector relay 1314 may be traced from positive potential at the lead 1316, through scratch key 34, 8 digital key 32, lead 1322, through winding of this relay, and thence to negative potential via lead 1307, reset key 33, and leads 1308 and 1302.

D8 relay 1314 in operating, at its lower intermediate front contact, closes a locking circuit therefor, which is readily apparent; at its lowermost front contact prepares a circuit for the counter in the totalizer; at its uppermost front contact closes a circuit for the B8 selector solenoid 1323, which circuit may be traced from positive potential at lead 1301 through said contact, lead 1324, through winding of B8 solenoid 1323 and thence to negative potential at lead 1309; at its upper intermediate front contact closes a circuit for the type bar solenoid 69 which may be traced from positive potential through said contact, lead 1311, terminal 9, lead 1411, winding of solenoid 69 and thence to negative potential via leads 1410 and 1402.

The A1 selector solenoid 1318, and the B8 selector solenoid 1323, as well as the type bar solenoids 66 and 69 operate to actuate the pins 71 and type bars 52, 53, respectively, to initiate cycling of the cam motor 274, in a manner similar to that already described for the test circuit. It is not believed necessary to trace the various circuits involved in the steps of printing and issuing the ticket as this has already been done during the test circuit operation. It is obvious that any other combination of numbers may be printed and issued in a similar manner, registration thereof being effected for each machine through the counter 35, the operating circuit for which may be traced from positive potential via lead 1403, rectifier 1433, lead 1434, contact 1428 of switch 273, lead 1436, terminal 8, and thence via lead 1326, through winding of counter 35, lead 1327, lead 1307, reset key 33, leads 1308 and 1302 to negative potential via lead 1402. Closure of make contact 1429 of switch 273 also renders effective a counter (not shown) in the totalizer, the circuit for which is of no interest herein.

In the Quiniela type of race, it is customary in issuing tickets that the first number be of a lower denomination than the second number, that is, low-high, and the ticket machine circuit, as shown in Fig. 13, is arranged so that the number in the upper rows of keys 32 must be struck first with the higher denomination key in the lower row sequentially operated. In other words, in a Quiniela combination such as 3-4, the number 3 key will be punched first in the upper row while the number 4 key will be punched

thereafter in the lower row. In this example, if the attendant had punched the number 4 key in the upper row first and the number 3 key in the lower row thereafter, the machine could not issue the desired ticket, as will appear herein-after.

The above is accomplished by serially connecting one source of potential, the negative potential in this instance, through the intermediate relays C2 to C7, inclusive. For example, in Fig. 13 relays C2 to C7, inclusive, are each shown provided at the top with an extra back contact 1328. Thus, it will be seen that the back contact 1328 of the C7 relay is connected to the lead 1307 and that this contact is also connected serially through the similar back contacts respectively of the C6, C5, C4, C3, and C2 relays. Further, it is to be noted that the back contact 1328 of the C7 relay is also connected via lead 1329 to the winding of the D7 selector relay in the lower bank of relays. Similarly, the back contacts of the C6, C5, C4, C3, and C2 relays are respectively connected in a similar manner to the D6, D5, D4, D3, and D2 relays.

Supposing, for instance, that the attendant had inadvertently struck digital key 7 in the upper row for a requested combination 6-7, or any combination having a first number less than 7, and had then struck the digital key 6, or such other number less than 6, in the lower bank thereafter. It will be obvious that relay D6 could not be energized, since operation of relay C7 had already opened the energizing path therefor at back contact 1328 and thereby precluded negative supply to the D6 relay.

Upon completion of the ticket selling period, which usually occurs a predetermined interval before the actual running of the race, the machine is locked by the steward who operates a key 1437 in his control box to the left, as viewed in Fig. 14, which key energizes the machine lock relay 1411 in a circuit that may be traced from negative potential through make contact of key 1437, terminal A, lead 1438, winding of relay 1411, and back to positive potential via lead 1439, terminal B and lead 1440. The machine lock relay 1411 in operating, at its lower break contact opens the positive supply of potential via lead 1412 to the selector relays in Fig. 13 and at its upper front contact prepares a path for energization of relays 83 and 98. It is to be noted that an extension 1442 is provided on the break contact 1409 and this extension 1442, upon being attracted by the relay 1411, is moved into locking engagement with a pivotal latch 1443, which is under control of a machine unlock relay 1444.

Upon such interruption of the positive supply, the hereinbefore described locking circuits for the C1 selector relay 1313 and D8 selector relay 1314 are likewise opened and these relays in releasing deenergize the respective A1 selector solenoid 1318 and B8 selector solenoid 1323, as well as the number bar solenoids 66 and 69. Relay 1415 also releases, since it is parallel to the winding of solenoid 66, and its back contact in retracting closes a circuit for the code change relay 83 and race change relay 98. The latter circuit may be traced from positive potential through lead 1440, terminal B, lead 1439, through parallel windings of solenoids 83 and 98, lead 1446, make contact of relay 1411, back contact of relay 1415, and thence to negative potential via lead 1402. Both code change and race change solenoids operate to actuate their respective bars 51 and 54 (see also Figs. 5 and 7), as described here-

inbefore. It will be readily apparent from the above circuit that relay 1415 prevents the operation of the race change and code change relays should the steward lock the machine while a ticket is in the process of being issued. Further, should the machine be locked just after the ticket is printed, the release of the selector relays will not prevent the further processing of the ticket, as the cam motor 274 will continue rotating with step-by-step operation of the solenoids 168, 234, 268, and 139 until the cycle is completed for issuance of the ticket. During the interim period the machines are tested by the service man and following the running of the race the machine is then released for the sale of tickets for the next race by the steward operating the key 1437 to the right, thereby releasing the machine lock relay 1411. Retraction of the make contact spring of the machine lock relay 1411 opens the hereinbefore traced energizing circuit for the code change relay 83 and race change relay 98, which likewise release. The machine unlock relay 1444, in response to actuation of key 1437, operates in a circuit that may be traced from the negative potential through key 1437 and right make contact, terminal C, lead 1447, winding of relay 1444, and thence over to positive potential via lead 1439, terminal B, and lead 1440. Relay 1444 in operating, attracts latch 1443, which releases extension 1442 and thereby permits the break contact 1409 to be retracted to its normally closed position. The machine is then in readiness for further issuance of tickets in accordance with the hereinbefore described procedure.

Figs. 15 and 16 combined with Fig. 14 illustrate a daily double circuit arrangement for horses; Figs. 17 and 14 illustrate a daily double circuit arrangement for dogs; Figs. 18 and 19 combined with Fig. 14 illustrate a circuit arrangement for horses for either win, place, or show; while Figs. 20 and 14 together illustrate a circuit arrangement for dogs for either win, place, or show. The various circuit arrangements are essentially similar to that already described in connection with Figs. 13 and 14, and it is accordingly not believed necessary to trace further the circuits for each such arrangement. However, since the upper number bar 53 is not required to be moved in a win, place, or show circuit arrangement, one row of selector relays and the corresponding row of selector solenoids is likewise not required, the upper number bar solenoid 69 being rendered ineffective in this instance, if supplied. In view of the immovability of the upper number bar the insulated contact 1414 thereon is by-passed and lead 1418 is connected to the cross bar 75 by a lead 1448, so as to provide a continuous circuit for operating the cam motor 274 upon movement of the lower number bar 52.

This will be brought out by considering a win, place, or show circuit arrangement, for example, the combination of Figs. 20 and 14. Assume that a ticket is requested of number 3 and the attendant has operated the corresponding key. In response thereto C3 selector relay 2013 is energized in a circuit that can be traced from positive potential via lead 1403, break contact 1404 of the motor running cam 286, lead 1407, break contact 198, lead 1408, break contact 1409, lead 1412, terminal 6, lead 2016, through normally closed scratch key 34, 3 digital key 32, and thence through winding of C3 relay 2013, lead 2007, reset key 33, and lead 2008 to negative potential via leads 2002 and 1402. C3 selector relay 2013 in operating, at its lower intermediate front con-

tact closes a locking circuit therefor, which circuit may be traced from positive potential at lead 2016, through lead 2017, said make contact, winding of C3 selector relay 2013, and thence to negative potential at lead 2007. At the lowermost front contact of C3 relay 2013, a circuit is prepared for the counter in the totalizer; at its uppermost front contact a circuit is closed for the A3 solenoid 2018; which circuit may be traced from positive potential at lead 2001, through said contact, lead 2019, through said solenoid winding, and thence to negative potential at lead 2002; at its upper intermediate front contact a circuit is closed for the type bar solenoid 66; which circuit may be traced from positive potential at lead 2001 through said contact, lead 2021, lead 2012, terminal 7, lead 1413, and thence through winding of solenoid 66 to negative potential via leads 1412 and 1402.

The A3 selector solenoid 2018 and type bar solenoid 66 operate to actuate the corresponding pin 71 and type bar 52, respectively, to initiate cycling of the cam motor 274. However, since the upper number bar 53 is immovable in this arrangement, the operating circuit for the cam motor 274 is slightly different from that heretofore described. Accordingly, the operating circuit for the cam motor 274 may now be traced from positive potential at lead 1406 through the parallel windings of the relay 1417 and cam motor 274, lead 1418, lead 1448, cross-bar 75, pin 71, tip 1416, and thence over lead 1402 to the negative potential. Operation of the relay 1417 and cam motor 274 initiates the cycling sequence and causes the machine to issue the ticket in the hereinbefore described manner.

From the foregoing description, it will be seen that the present invention provides an improved machine which is adapted for issuing one or two numbered tickets. The ticket issuing machine is simple in construction, economical to manufacture, easy to assemble, and is effective and practical in operation. The machine is rugged in construction and is adapted for continuous and hard usage.

As various changes may be made in the form, construction and arrangement of the parts herein, without departing from the spirit and scope of the invention and without sacrificing any of its advantages, it is to be understood that all matters are to be interpreted as illustrative and not in any limiting sense.

What is claimed is:

1. A machine for printing and issuing tickets comprising, in combination, a stationary bar having therein a longitudinal slot and a plurality of spaced transverse openings intersecting said longitudinal slot, a bar having a plurality of printing type characters on the face thereof movable in said slot, a plurality of pins slidable in said transverse openings, a plurality of digital keys each corresponding to one of the characters on said movable bar, and electromechanical means responsive to actuation of one of said keys for moving said movable bar, moving one of said pins ahead of and across the path of said movable bar to interrupt movement of said movable bar, printing the character corresponding to said one key onto a ticket, and ejecting the printed ticket from the machine.

2. A machine for printing and issuing tickets comprising, in combination, a stationary bar having therein a longitudinal slot and a plurality of spaced transverse openings intersecting said longitudinal slot, a bar having a plurality of printing type characters on the face thereof movable

in said slot, a plurality of pins slidable in said transverse openings, a plurality of digital keys each corresponding to one of the characters on said movable bar, electromechanical means responsive to actuation of one of said keys for moving said movable bar and one of said pins ahead of and into the path of said movable bar so as to stop said movable bar at a predetermined point, and electromechanical means responsive to engagement between said movable bar and said one of said pins for printing the character corresponding to said one key onto a ticket and ejecting the printed ticket from the machine.

3. A machine for printing and issuing tickets comprising, in combination, a stationary bar having therein a longitudinal slot and a plurality of spaced transverse openings intersecting said longitudinal slot, a bar having a plurality of printing type characters on the face thereof movable in said slot, a metallic tip portion at the forward end of said movable bar insulated from the body of said movable bar, a plurality of metallic pins slidable in said transverse openings, each of said pins being insulated from said stationary bar, a plurality of digital keys each corresponding to one of the characters on said movable bar, and electromechanical means responsive to actuation of one of said keys for moving said movable bar and one of said pins ahead of and into the path of the movable bar to stop said movable bar at a predetermined point, and electromechanical means responsive to contact between said tip portion and said one pin for printing the character corresponding to said one key onto a ticket and ejecting the printed ticket from the machine.

4. A machine for printing and issuing tickets comprising, in combination, a stationary bar having therein a pair of longitudinal slots and a plurality of spaced transverse openings intersecting said longitudinal slots, a pair of bars having type on the face thereof movable in said slots, a metallic tip portion at the forward end of each of said movable bars insulated from the bodies thereof, a plurality of metallic pins slidable in said transverse openings, said pins being insulated from said stationary bar and being electrically interconnected, a plurality of digital keys each corresponding to the respective type on said movable bars, and electromechanical means including a slidable platen responsive to actuation of two of said keys for moving said bars and selected pins ahead of and into the paths of the respective movable bars to stop said bars at predetermined points, and electromechanical means responsive to contacts between said tip portions and pins for printing the type corresponding to said two keys onto a ticket and ejecting the printed ticket from the machine.

5. A machine for printing and issuing tickets comprising, in combination, a stationary bar having therein a longitudinal slot and a plurality of spaced transverse openings intersecting said longitudinal slot, a bar having a plurality of type on the face thereof movable in said slot, an insulated metallic tip portion at the forward end of said movable bar insulated from the body thereof, a plurality of metallic pins slidable in said transverse openings, sleeve means for insulating said pins from said stationary bar, a metallic tie bar for electrically interconnecting said pins, a plurality of digital keys each corresponding to the respective type on said movable bar, electromechanical means responsive to actuation of one of said keys for moving said movable bar and a selected one of said pins ahead

of and across the path of said movable bar, whereby said movable bar is interrupted at a predetermined point with the tip portion thereof in contact with the moved pin, electromechanical means rendered effective upon said contact, a 5 slideable platen responsive to said last electromechanical means for printing the type corresponding to said one key onto a ticket, and electromechanical means responsive to said last electromechanical means following movement of said 10 slideable platen for ejecting the printed ticket from the machine.

6. A machine for printing and issuing tickets comprising, in combination, a stationary bar having therein a longitudinal slot and a plurality of spaced transverse openings intersecting said longitudinal slot, a bar having a plurality of type on the face thereof movable in said slot, an insulated metallic tip portion at the forward end of said movable bar, a plurality of metallic pins 20 slideable in said transverse openings, said pins being insulated from said stationary bar and being electrically interconnected, a plurality of digital keys each corresponding to the respective type on said movable bar, electromechanical means responsive to actuation of one of said keys for moving said movable bar and a selected one of said pins ahead of and across the path of said movable bar, whereby said movable bar is interrupted at a predetermined point with the tip portion thereof in contact with the moved pin, electromechanical timing means including a plurality of cams rendered effective upon said contact, a slideable platen responsive to one of said 25 cams on said timing means for printing the type corresponding to said one key onto a ticket, and electromechanical means responsive to another of said cams on said timing means following movement of said slideable platen for ejecting the printed ticket from the machine.

7. A machine for printing and issuing tickets comprising, in combination, a stationary bar having therein a longitudinal slot and a plurality of spaced transverse openings intersecting said longitudinal slot, a bar having a plurality of type on the face thereof movable in said slot, an insulated metallic tip portion at the forward end of said movable bar, a plurality of insulated metallic pins slideable in said transverse openings, a plurality of digital keys corresponding to the respective type on said movable bar, electromechanical means responsive to actuation of one of said keys for moving said type bar and a selected one of said pins ahead of and across the path of said movable bar, whereby the type corresponding to said actuated key is placed in a printing position by contact of said tip portion with said selected pin, second electromechanical means including a slideable platen responsive to said contact for abuttingly engaging said type bar to imprint the type corresponding to said actuated key onto a ticket, and third electromechanical means responsive to said second electromechanical means for ejecting the printed ticket from the machine.

8. A machine for printing and issuing tickets comprising, in combination, a stationary bar having therein a longitudinal slot and a plurality of spaced transverse openings intersecting said longitudinal slot, a bar having a plurality of type on the face thereof movable in said slot, an insulated metallic tip portion at the forward end of said movable bar, a plurality of insulated metallic pins slideable in said transverse openings, a plurality of digital keys corresponding to the respective type on said movable bar, electromechanical

means responsive to actuation of one of said keys for moving said type bar and a selected one of said pins ahead of and across the path of said movable bar, whereby the type corresponding to said actuated key is placed in a printing position by contact of said tip portion with said selected pin, an electric motor with a plurality of angularly spaced cams rendered effective upon said contact being made, second electromechanical means including a slideable platen responsive to a first one of said cams for abuttingly engaging said type bar to imprint the type corresponding to said actuated key onto a ticket, and third electromechanical means responsive to a second one of said cams for ejecting the printed ticket from the machine.

9. A machine for printing and issuing tickets comprising, in combination, a stationary bar having therein a longitudinal slot and a plurality of spaced transverse openings intersecting said longitudinal slot, a bar having a plurality of type on the face thereof movable in said slot, an insulated metallic tip portion at the forward end of said movable bar, a plurality of insulated metallic pins slideable in said transverse openings, a plurality of digital keys corresponding to the respective type on said movable bar, electromechanical means responsive to actuation of one of said keys for moving said type bar and a selected one of said pins ahead of and across the path of said movable bar, whereby the type corresponding to said actuated key is placed in a printing position by contact of said tip portion with said selected pin, an electric motor with a plurality of angularly spaced cams rendered effective upon said contact being made, second electromechanical means including a slideable platen responsive to a first one of said cams for abuttingly engaging said type bar to imprint the type corresponding to said actuated key onto a ticket, third electromechanical means responsive to a second one of said cams for ejecting the printed ticket from the machine, and fourth electromechanical means responsive to movement of said ticket for registering issuance of said ticket.

10. A machine for printing and issuing tickets comprising, in combination, a paper supply roll for said tickets, a stationary bar having therein a longitudinal slot and a plurality of spaced transverse openings intersecting said longitudinal slot, a bar having a plurality of type on the face thereof movable in said slot, an insulated metallic tip portion at the forward end of said movable bar, a plurality of insulated metallic pins slideable in said transverse openings, a plurality of digital keys corresponding to the respective type on said movable bar, electromechanical means responsive to actuation of one of said keys for moving said type bar and a selected one of said pins ahead of and across the path of said movable bar, whereby the type corresponding to said actuated key is placed in a printing position by contact of said tip portion with said selected pin, an electric motor with a plurality of angularly spaced cams rendered effective upon said contact being made, second electromechanical means including a slideable platen responsive to a first one of said cams for abuttingly engaging said type bar to imprint the type corresponding to said actuated key onto a ticket carried on said paper supply roll, third electromechanical means responsive to a second one of said cams for moving said printed ticket a predetermined distance, fourth electromechanical means responsive to a third one of said cams for cutting said ticket from said supply roll, fifth

electromechanical means responsive to a fourth one of said cams for ejecting the printed ticket from the machine, and sixth electromechanical means responsive to ejecting movement of said ticket for registering issuance of said ticket.

11. A machine for printing and issuing a ticket comprising, in combination, a stationary bar having therein a longitudinal slot and a plurality of spaced transverse openings intersecting said longitudinal slot, a bar having a plurality of type on the face thereof movable in said slot, an insulated metallic tip at the forward end of said movable bar, a plurality of metallic pins slidable in said transverse openings, means for insulating each of said pins from said stationary bar, a plurality of digital keys corresponding to the respective type on said movable bar, an electric circuit rendered effective upon actuation of one of said digital keys, a second circuit responsive to said first circuit for effecting movement of said movable bar, a third circuit responsive to said first circuit for moving one of said pins ahead of and into the path of said movable bar to stop said bar at a predetermined point and thereby select the type corresponding to the actuated key, and a fourth circuit responsive to contact between said actuated pin and the tip of said movable bar for impressing the selected type on a ticket and ejecting the ticket from the machine.

12. A machine for printing and issuing a ticket comprising, in combination, a stationary bar having therein a longitudinal slot and a plurality of spaced transverse openings intersecting said longitudinal slot, a bar having a plurality of type on the face thereof movable in said slot, an insulated metallic tip at the forward end of said movable bar, a plurality of metallic pins slidable in said transverse openings, means for insulating each of said pins from said stationary bar, a plurality of digital keys corresponding to the respective type on said movable bar, an electric circuit rendered effective upon actuation of one of said digital keys, a second circuit responsive to said first circuit for effecting movement of said movable bar, a third circuit responsive to said first circuit for moving one of said pins ahead of and into the path of said movable bar to stop said bar at a predetermined point and thereby set the selected type corresponding to the actuated key in a printing position, a fourth circuit including a motor with angularly spaced cams rendered effective upon contact of said actuated pin and the tip of said movable bar, a fifth circuit including a printing solenoid rendered effective by one of said cams for impressing the selected type on a ticket, and a sixth circuit including an ejector solenoid rendered effective by a second one of said cams for ejecting said ticket from the machine.

13. A machine for printing and issuing a ticket comprising, in combination, a stationary bar having therein a longitudinal slot and a plurality of spaced transverse openings intersecting said longitudinal slot, a bar having a plurality of type on the face thereof movable in said slot, an insulated metallic tip at the forward end of said movable bar, a plurality of metallic pins slidable in said transverse openings, means for insulating each of said pins from said stationary bar, a plurality of digital keys corresponding to the respective type on said movable bar, an electric circuit including a relay rendered effective upon actuation of one of said digital keys, a second circuit including a type bar solenoid rendered effective upon operation of said relay to effect movement of said movable

5

bar, a third circuit including a solenoid also rendered effective upon operation of said relay to move one of said pins corresponding to the actuated key ahead of and into the path of said movable bar, a fourth circuit including a motor with angularly spaced cams rendered effective upon contact being made between said actuated pin and the tip of said movable bar, a fifth circuit including a printing solenoid rendered effective by one of said cams for impressing the selected type on a ticket, a sixth circuit including an ejector solenoid rendered effective by a second one of said cams for ejecting said ticket from the machine, and a seventh circuit including an electromagnetic counter rendered effective during ejection of said ticket for registering the issuance of said ticket.

14. A machine for printing and issuing a ticket comprising, in combination, a paper supply roll for said tickets, a stationary bar having therein a longitudinal slot and a plurality of spaced transverse openings intersecting said longitudinal slot, a bar having a plurality of type on the face thereof movable in said slot, an insulated metallic tip at the forward end of said movable bar, a plurality of metallic pins slidable in said transverse openings, means for insulating each of said pins from said stationary bar, a plurality of digital keys corresponding to the respective type on said movable bar, an electric circuit including a relay rendered effective upon actuation of one of said digital keys, a second circuit including a type bar solenoid rendered effective upon operation of said relay to effect movement of said movable bar, a third circuit including a solenoid rendered effective simultaneously with said second circuit upon operation of said relay to move the corresponding one of said pins ahead of and into the path of said movable bar, a fourth circuit including a motor with angularly spaced cams rendered effective upon contact between said actuated pin and the tip of said movable bar, a fifth circuit including a printing solenoid rendered effective by one of said cams for impressing the selected type on a ticket carried on said paper supply roll, a sixth circuit including a ticket paper roll moving solenoid rendered effective by a second one of said cams for moving said printed ticket a predetermined distance, a seventh circuit including a cutting solenoid rendered effective by a third one of said cams for severing said ticket from the paper roll, an eighth circuit including an ejector solenoid rendered effective by a fourth one of said cams for ejecting severed ticket from the machine, and a ninth circuit including an electromagnetic counter rendered effective during ejection of said severed ticket for registering the issuance thereof.

60

15. A machine for printing and issuing a ticket comprising, in combination, a paper supply roll for said tickets, a stationary bar having therein a pair of longitudinal slots and a plurality of spaced transverse openings intersecting said longitudinal slots, a pair of bars having a plurality of type on the faces thereof movable in said slots, an insulated metallic tip at the forward end of each of said movable bars, a plurality of metallic pins slidable in said transverse openings, means for insulating each of said pins from said stationary bar, a plurality of digital keys arranged in two rows, each row having keys corresponding to the respective type on said movable bars, a pair of electric

70

75

circuits each including a relay rendered effective upon actuation of one of said digital keys in each of said rows, a second pair of circuits each including a type bar solenoid rendered effective upon operation of said relays to effect movement of said pair of movable bars, a third pair of circuits each including a solenoid rendered effective simultaneously with said second pair of circuits upon operation of said relays to move the corresponding ones of said pins ahead of and into the paths of said movable bars, a fourth circuit including a motor with angularly spaced cams rendered effective upon respective contact between said actuated pins and the tips of said movable bars, a fifth circuit including a printing solenoid rendered effective by one of said cams for impressing the selected type on a ticket carried on said paper supply roll, a sixth circuit including a ticket paper roll moving solenoid rendered effective by a second one of said cams for moving said printed ticket a predetermined distance, a seventh circuit including a cutting solenoid rendered effective by a third one of said cams for severing said ticket from the paper roll, an eighth circuit including an ejector solenoid rendered effective by a fourth one of said cams for ejecting said severed ticket from the machine, and a ninth circuit including an electromagnetic counter rendered effective during ejection of said severed ticket for registering the issuance thereof.

16. In a ticket issuing mechanism, a stationary bar having a pair of superposed longitudinal slots, a type bar slidable in each of said slots, means in said stationary bar for arresting said type bars, electromechanical means for selectively controlling said type bars and arresting means, a strip of ticket paper, a slideable platen for printing selected type of said type bars on said ticket paper, means for moving said strip of ticket paper, means for severing the printed ticket from said strip, means for ejecting said severed ticket, and electromechanical means responsive to engagement between said type bars and arresting means for controlling in sequential order operation of the slideable platen, paper strip moving means, severing means, and ejecting means.

17. In a ticket issuing mechanism, a stationary bar having a pair of superposed longitudinal slots, a type bar slidable in each of said slots, means in said stationary bar for arresting said type bars, electromechanical means for selectively controlling said type bars and arresting means, a strip of ticket paper, a slideable platen for printing selected type of said type bars on said ticket paper, means for moving said strip of ticket paper, means for severing the printed ticket from said strip, means for ejecting said ticket, means for registering ejection of the ticket, and electromechanical means responsive to engagement between said type bars and arresting means for controlling in sequential order operation of the slideable platen, paper strip moving means, severing means, ejecting means, and registering means.

18. In a ticket issuing mechanism, a stationary bar having a pair of longitudinal slots, a type bar slidable in each of said slots, means in said stationary bar for arresting said type bars, a plurality of digital keys, electromechanical means responsive to actuation of two of said keys for selectively controlling said type bars and arresting means, a strip of ticket paper, a movable platen for printing selected type of said type bars on said ticket paper, means for moving said strip,

a mechanism for severing the printed ticket paper from said strip, means for ejecting said ticket paper, means for registering said ejection of the ticket paper, and electromechanical means responsive to engagement between said type bars and arresting means for controlling in sequential order the printing platen, and moving, severing, ejecting and registering means.

19. In a ticket issuing mechanism, a stationary bar having a pair of longitudinal slots, a type bar slidable in each of said slots, means in said stationary bar for arresting said type bars, a plurality of digital keys, electromechanical means responsive to actuation of two of said keys for selectively controlling said type bars and arresting means, a strip of ticket paper, a movable platen for printing selected type of said type bars on said ticket paper, means for moving said strip following movement of the printing platen, a mechanism including a pivotal cutting blade for severing the printed ticket paper from said strip, means including a pair of rollers frictionally engageable with said tickets for ejecting said ticket paper from the machine, means including a counter for registering said ejection of the ticket, and electromechanical means responsive to engagement between said type bars and arresting means for controlling in sequential order the printing platen, and moving, severing, ejecting and registering means.

20. In a ticket issuing mechanism, a plurality of keys representing different digital values, a reciprocating number bar, means including an electromagnetic device responsive to operation of one of said digital keys for moving and then holding said number bar at a predetermined position, a type bar, an electromagnetic escapement device for moving said type bar step-by-step, and an electromagnetic device responsive to operation of said one digital key for rendering ineffective said escapement device.

21. In a ticket issuing mechanism, a stationary bar having a plurality of longitudinal slots, a type bar slidable in each of said slots, a plurality of digital keys, electromechanical means responsive to actuation of one of said keys for selectively controlling movement of one of said type bars, an electromagnetic device responsive to said electromechanical means for moving and then holding said one type bar at a predetermined position, an electromagnetic escapement device for moving another of said type bars step-by-step, a second electromagnetic device responsive to said electromechanical means for rendering ineffective said escapement device, a control key, and an electromagnetic device in response to actuation of said control key to render said escapement device effective to move said other type bar one step only following release of said second electromagnetic device.

22. In a ticket issuing mechanism, a stationary bar having a plurality of longitudinal slots, a type bar slidable in each of said slots, a plurality of digital keys, electromechanical means responsive to actuation of one of said keys for selectively controlling one of said type bars, means including an electromagnetic device responsive to said electromechanical means for moving and holding said one type bar at a predetermined position, a pair of electromagnetic escapement devices connected in parallel for moving a pair of said type bars step-by-step, a second electromagnetic device in parallel with said first electromagnetic device also responsive to said electromechanical means for rendering ineffective said

escapement devices, a control key, and a third electromagnetic device in response to actuation of said control key to render said escapement device effective to move said pair of type bars one step only following release of said second electromagnetic device.

23. In a ticket issuing mechanism, a stationary bar having a plurality of longitudinal slots, a type bar slideable in each of said slots, a plurality of digital keys, electromechanical means responsive to actuation of one of said keys for selectively controlling one of said type bars, means including an electromagnetic device responsive to said electromechanical means for moving and then holding said one type bar at a predetermined position, a pair of electromagnetic escapement devices connected in parallel for simultaneously moving a pair of said type bars step-by-step, a second electromagnetic device in parallel with said first electromagnetic device also responsive to said electromechanical means for rendering ineffective said escapement devices, a control key, a third electromagnetic device with an extension on its armature responsive to actuation of said control key to one operative position to render said escapement devices effective to move said pair of type bars one step only following release of said second electromagnetic device, and latch means engageable with said armature extension upon operation of said third electromagnetic device for maintaining said electromechanical means ineffective.

24. In a ticket issuing mechanism, a stationary bar having a plurality of longitudinal slots, a type bar slideable in each of said slots, a plurality of digital keys, electromechanical means responsive to actuation of one of said keys for selectively controlling one of said type bars, means including an electromagnetic device responsive to said electromechanical means for moving and then holding said one type bar at a predetermined position, a pair of electromagnetic escapement devices connected in parallel for simultaneously moving a pair of said type bars step-by-step, a second electromagnetic device in parallel with

said first electromagnetic device also responsive to said electromechanical means for rendering ineffective said escapement devices, a control key having two operative positions, a third electromagnetic device with an extension on its armature responsive to actuation of said control key to one operative position to render said escapement devices effective to move said pair of type bars one step only following release of said second electromagnetic device, latch means engageable with said armature extension upon operation of said third electromagnetic device for maintaining said electromechanical means ineffective, and a fourth electromagnetic device for controlling said latch means, said fourth device being responsive to movement of the control key to the other operative position to release said latch from said extension and thereby permit operation of said electromechanical means.
